UNITED STATES PATENT OFFICE

LESTER S. GUNDERMAN, OF PITTSBURGH, PENNSYLVANIA

GRAVITY TOY OR GAME

Application filed December 23, 1927. Serial No. 242,034.

This invention is for a novel amusing gravity toy or game, which may be utilized purely as a toy.

My object being the provision of a simple inexpensive arrangement involving in its operation, the movement of marbles or like objects passing over inclined runways, the rocking of one runway will release spherical objects automatically, one at a time from a magazine and discharge them at the end of said runway onto a base.

This invention is illustrated in the accompanying drawing, in which,

Fig. 1 represents a section view of the toy with the rocking runway shown in its two extreme positions.

Fig. 2 is a top plan view of the device.

Fig. 3 is a fragmentary sectional view showing the upper end of the rocking runway in its extreme upper position.

In the drawing, 5 designates an integral base which is preferably formed of sheet metal having rounded upward extended edges of sufficient height to retain the marbles or other like spherical objects as they are discharged onto the base, the holes 6 are used in scoring when the device is used as a game.

The upright 7 is attached to the base 5, and is formed from light gauge sheet steel into a channel shaped cross section, which insures great stiffness with minimum weight. Secured to the upper end of the upright 7 is an inclined magazine 8, likewise made from light gauge steel, said magazine is sufficiently inclined to enable the marbles to roll by gravity towards its forward or lower end, which is provided with an opening 9 through which marbles or the like pass.

A rocking runway 10, made preferably from one strip of metal is fulcrumed at point 11 and supported on the upright 7 by a wire pin 12 passing through these members. The sloping tongued end portion 13 of the rocking runway 10 is formed in such a position that spherical objects such as marbles in passing over the end of the magazine 8, and through the opening 9, force the upper end of the said runway to move downward and the extreme 50 tongued portion 14 thereof to prevent the

succeeding marbles or like spherical objects from immediately following the preceding marbles until they reach the lower end of the said runway.

The tongued end 14 of the rocking runway 55 when at its lowest position abuts the top edge of the magazine 8, and when at its uppermost position, the tongue portion 13 abuts the end of the magazine 8, this action indexes one marble at a time through the opening 9 of the 60 magazine 8.

The lower portion 15 of the rocking runway 10 is formed in an upwardly direction so that a marble or a like object rolling down the rocking runway will strike the raised part 65 15 which arrests the speed thereof, and assists the weight of the marble or such spherical objects in rocking the runway 10.

The lower end of 16 of the rocking runway 70 10 is closed to prevent the marbles from rolling out of the end thereof; an opening 17 is provided in the bottom of the said runway to discharge the marbles or such like objects on the said base 5.

When in operation the marbles or like objects are placed in the magazine 8, the end 75 14 of the rocking runway acts as a stop for the marbles. In order to start the movement of the marbles the upper end of the rocking runway 10 is raised, the first marble starts to roll and strikes the portion 13, which causes the end of the runway to rock downward until the marble is released under the lower end of the magazine 8, said marble will pass down the runway and strike the lower portion 15 thereof and will rock the runway 10 in a reverse direction, and so release the next marble, which has moved up to the end 85 15 of the rocking runway 10, as the first marble strikes the portion 13 of the rocking runway 10 and forces the end 14 downward it will act as a stop for the succeeding marble, so that it cannot follow rapidly in the path of the marble just released. In this manner 90 the marbles one by one are automatically released from the magazine 8 and pass down the rocking runway 10, the rocking action of this member will always release a marble and a continuous operation is assured until all 100

the marbles have been discharged on to the base 5.

What I claim is:—

1. An automatic toy, the combination of an upright, a magazine at the upper end of the upright, a rocking runway pivotally mounted on the said upright, a tongue bent upward and backward at the upper end of the runway, said tongue being so positioned that marbles contacting with the upward bent portion when passing over the end of said magazine rock the runway downward whereby said marbles or such like spherical objects are delivered one at a time onto the said runway to be discharged at the other end thereof.
2. An automatic toy, the combination of an upright, a detachable base for said upright, an inclined magazine supported thereby, a rocking runway pivotally supported below the magazine, one end of said runway having an upwardly bent tongue extending above the end of said magazine and in contact therewith, the lower end of said runway having a discharge opening and a raised surface above the discharge opening and so positioned that the weight of spherical objects passing over the said raised portion will rock the runway.
3. An automatic toy, the combination of an upright, a detachable base for said upright, an inclined magazine supported on said upright, a rocking runway pivotally supported on said upright below the magazine, the lower end of said runway having a discharge opening and a portion above the discharge opening, the upper end of said runway having a tongue bent upwardly and backward to contact with the magazine and deliver marbles one at a time onto the runway by the rocking motion of the said runway.
4. An automatic toy, the combination of a detachable base, an upright mounted thereon, a magazine supported at the upper end thereof, a rocking runway pivotally supported on the upright below the magazine, one end of said runway having a discharge opening at the bottom end thereof, the top end of said runway having an upward and reversely bent tongue to contact with the end of said magazine to deliver marbles one at a time onto said runway by the rocking motion thereof and discharge marbles through the said opening onto the said base.

In testimony whereof I affix my signature.
LESTER S. GUNDERMAN.
